UNITED STATES PATENT OFFICE.

ALLEN BURNIP DARBYSON, OF PHILIPSBURG, QUEBEC, CANADA.

STRAIGHT-EDGE GUIDE.

1,043,905.

Specification of Letters Patent. Patented Nov. 12, 1912.

Application filed March 25, 1912. Serial No. 686,118.

To all whom it may concern:

Be it known that I, ALLEN B. DARBYSON, a subject of the King of Great Britain, residing at Philipsburg, Province of Quebec,

5 Canada, have invented certain new and useful Improvements in Straight-Edge Guides; and I do hereby declare that the following is a full, clear, and exact description of the invention, such as will enable others skilled 10 in the art to which it appertains to make and use the same.

The invention to be hereinafter described relates to a straight-edge or T square guide.

In order to more clearly disclose the construction, operation, and use of the invention, reference should be had to the accompanying drawings forming part of the present application.

Throughout the several figures of the 20 drawings like reference characters designate the same parts.

In the drawings: Figure 1 is a top plan of the invention, applied; Fig. 2 is a side view of one member; Fig. 3 is an end view 25 of the same; Fig. 4 is a bottom plan view of the same; Fig. 5 is a top plan view of the invention applied to a T square; and Fig. 6 is a side view of the same.

The main objects of the invention are to 30 provide a simple, efficient, durable, economical, and compact straight-edge or T square guide which may be readily and quickly applied.

Referring to the drawings in detail, 1 35 indicates a straight-edge such as is in common use by most draftsmen. A U shaped metal clip 2 embraces the edge of this straight-edge near each of its ends. The distance between the arms or branches of 40 this clip is considerably greater than the thickness of the straight-edge. Embracing the upper arm of this clip is a somewhat similar clip 3. An adjusting screw 4 is passed freely through the upper arm of clip 45 3, threaded through the upper arm of clip 2, and bears against the lower arm of clip 3. The result of this construction is the movement of the arms of clip 2 toward or from the arms of clip 3, as the screw 4 is 50 turned in one direction or the other. As the lower arm of clip 3 is forced toward the lower arm of clip 2, the straight-edge will be clamped securely between them.

The lower arm of the clip 2 is formed with 55 a tail or extension 5 to which is pivotally connected the index point 6 of a bar or

head 7. The under face of the tail or extension is provided with graduations which coöperate with the index needle or point. The pivotal connection acts as a center, and 60 the coöperating graduations and index needle indicate the relative angular adjustments between the tail 5 and head 7. In order to secure the parts in adjusted positions, a threaded pin 8 and nut 9 are used. 65 The pin projects from the tail and slides freely in an arcuate slot 10 in the base of the point 6. By turning the nut down on the threaded pin, the parts may be positively bound or secured in any desired adjustment. 70 The construction thus far described is duplicated for each end of the straight-edge.

The head 7 for one end of the straight-edge is provided with a simple set of anti-friction rollers 11 adapted to engage the 75 edge of the drawing board and lessen the friction which would otherwise exist. The other head, is provided with sets of clamping clips 12 and 13, and coöperating screws 14, generally similar in construction, operation, and use to the clips 2 and 3, and bolts 4. Each clip 12 however, is provided with an off set flange 15 from which is supported a horizontal antifriction guide roller 16 adapted to engage the edge of the drawing 80 board; as in the right hand portion of Fig. 1. Also, each of the clips 13 carries a small vertical antifriction guide roller 17 adapted to engage the top surface of the drawing board. The clips 12 and 13 with their 85 screws 14, may be applied equally well either to the heads 7 or to the end of a straight-edge. Figs. 5 and 6 show the latter application. When used as in Figs. 5 and 6, a guide bar or plate 18 should be provided 90 on the drawing board. The thickness of the vertical wall of this bar or plate should be just equal to the distance between the edge of the horizontal guide wheel 16 and the adjacent face of the vertical guide roller 100 17. In this way, all relative lateral movement between the straight-edge of the guide bar will be prevented, and the movement of the straight-edge across the board will be kept perfectly true. 105

It is thought that the operation and use of the invention will be clear from the preceding detailed description.

Changes may be made in the construction, arrangement, and disposition of the several 110 parts of the invention without in any way departing from the field and scope of the

same, and it is meant to include all such within this application wherein only preferred forms have been disclosed.

Having thus fully described my invention, 5 what I claim as new and desire to secure by Letters Patent is:

1. In combination, a straight-edge, two pairs of coöperating clips adapted to be clamped to the straight-edge near its opposite ends, one clip of each pair being provided with an extension having a set of graduations, heads provided with index points each having an arcuate slot, pivotal connections between each head and one of 10 said extensions, antifriction devices carried by each head and adapted to engage the edge of a drawing board, a pin projecting from each of the aforesaid extensions and playing in each of said arcuate slots, and a 15 binding nut threaded upon each pin.

2. In combination, a straight-edge, a pair of coöperating clips adapted to be clamped thereto, one of said clips being provided

with an extension having a set of graduations, a head provided with an index point, 25 pivotal connections between said head and said extension, and antifriction devices carried by said head.

3. In combination, a straight-edge, a pair of coöperating clips adapted to be clamped 30 thereto, one of said clips being provided with an extension having a set of graduations, a head provided with an index point and having an arcuate slot, a pin projecting from the aforesaid extension and playing 35 in said arcuate slot, a binding nut threaded upon said pin, pivotal connections between said head and said extension, and antifriction devices carried by said head.

In witness whereof I have hereunto set 40 my hand in the presence of two witnesses.

ALLEN BURNIP DARBYSON.
